Specification for Design.

Patented Aug. 19, 1919.

Application filed April 18, 1919. Serial No. 291,147. Term of patent 3½ years.

To all whom it may concern:

Be it known that I, WILLIAM TURTON, a subject of the King of Great Britain, residing at Newark, in the county of Essex and State of New Jersey, have invented a new, original, and ornamental Design for Hand-Bag Frames, of which the following is a specification, reference being had to the accompanying drawing, forming part thereof.

The figure is a front elevational view of a hand-bag frame, showing my new design.

I claim:

The ornamental design for a hand-bag frame, as shown.

WILLIAM TURTON.
